SHIP CONSTRUCTION

John H. Odenbach, Rochester, N. Y., assignor to
 Odenbach Holding Corporation, Rochester,
 N. Y., a corporation of New York

Application February 7, 1941, Serial No. 377,882

40 Claims. (CL 114—79)

This invention relates to an improved method of ship construction and the product of such a method.

In my prior patents, 1,970,182 of August 14, 1934; 2,018,865 of October 29, 1935 and 2,104,053 of January 4, 1938 and in my co-pending application of March 25, 1939, Serial No. 264,090, now Patent 2,279,091 of April 7, 1942, I have described novel apparatus and methods of constructing the hull of a ship and this application is particularly directed to improvements in such methods and to ships constructed thereby.

In my co-pending application of March 25, 1939, Serial No. 264,090, I have shown a method of forming the bow and stern portions of a ship's hull to obtain the necessary curvilinear and converging sides of the structure. In that application a plurality of members, each having tapered legs, are positioned in adjoining relation to form the curved sides of the bow and stern sections, the individual members being fabricated with tapered legs, prior to incorporation in the hull structure.

In brief, the method of ship construction disclosed in this application comprises the joining together of a plurality of members to form a tubular rectangular structure having substantially parallel walls; cutting a piece from each of two oppositely disposed walls at the bow and at the stern of said tubular structure to leave projections from the amidships portion of the tubular structure; cutting transverse pieces out of certain of said projections, (if the curved corner construction (as shown) is used) deflecting the same projections inwardly to bring the edges of the cut-outs into contact and joining said contacting edges to complete the hull structure.

As will be described hereinafter, modifications of this general concept may be used to advantage and by changing the shape of the initial tubular section and the shape of the cut-outs wide latitude of design may be obtained. An open top section would be used to obtain an open or undecked boat or barge.

A principal object of this invention is to provide an economical, rapid and strong construction for ship hulls.

A further principal object of this invention is to provide a method whereby a hull may be constructed entirely from standard structural shapes with a minimum of fabrication required prior to incorporation into the hull.

A further principal object of this invention is to provide a method particularly adapted for

"line production" because the several units, forming the initial "set-up" or hull assembly, will be similar in design and size.

A further object of the invention is the elimination of much costly engineering, design, layout and loft work.

A further object of the invention is the use of a construction method adapted to use welded joints between the members and to enable the use of automatic welding equipment for most of the work.

A further object of the invention is to secure a great variation of line or contour in the hull in a simple and economical manner.

A further object of the invention is to provide a method which can be practiced with a minimum of shipyard equipment.

A particular object of the invention is the method used to assure bending of the hull surfaces at the desired points during the deflecting operation.

A further object of the invention is to provide a method of ship construction whereby a plurality of members may be aligned straight in a jig and thereafter given the true curvilinear surface desired in the hull, with a minimum of labor, expense and skill being required.

A further object of the invention is to provide a method of ship construction whereby automatic welding equipment may be used for the straight flat welds required in the construction of the initial hull structure, before cutting and deflection to form the bow and stern, or end portions, of the hull.

To these and other ends the characteristic features and advantages of my improvements will more fully appear in the following description and the accompanying drawings in illustration thereof.

In the drawings in which like reference numerals designate like parts,

Fig. 1 is a diagrammatic plan view of an initial hull structure assembly.

Fig. 2 is a section taken on the plane A—B of Fig. 1.

Fig. 3 is a diagrammatic plan view of the structure of Fig. 1 after the cutting and removal of sections from the top deck and bottom of the hull, leaving cut-outs as shown.

Fig. 4 is a sectional view taken on the plane C—D of Fig. 3.

Fig. 5 is a diagrammatic plan view of the structure shown in Fig. 3 after the hull side walls have been deflected inwardly into position to form the bow of the ship.

Fig. 6 is a section taken on the plane E—F of Fig. 5.

Fig. 7 shows a modified form of the invention and is a diagrammatic plan view of a hull structure after the cutting of sections of proper size from the upper deck and bottom of the structure to provide deck overhang in the bow of the completed hull.

Fig. 8 is a section taken on a plane G—H of Fig. 7.

Fig. 9 is a diagrammatic plan view of the structure shown in Fig. 7 after the hull sides have been brought into position to form a portion of the bow, the dotted lines showing the additional structure necessary to complete the bow of the hull.

Fig. 10 is a section taken on the plane J—K of Fig. 9.

Fig. 11 is a side elevation of the complete structure shown in Fig. 9 and also shows the layout of the additional structural members embodied in the extreme forward position of the bow.

Fig. 12 is a plan view showing the arrangement of the structural members in the bow of a hull constructed in accordance with the invention.

Fig. 13 is a plan view of one of the walls of the structure shown in Figs. 3 or 7 and discloses the method of transverse cutting employed to secure proper bending when bringing the projecting walls into final position.

Fig. 14 is a diagrammatic side view of an initial hull structure assembly similar to Fig. 1.

Fig. 15 is a section taken on the plane L—M of Fig. 14.

Fig. 16 is a diagrammatic side view of the structure of Fig. 14 after the cutting of sections from the side walls of the hull leaving cut-outs or openings as shown.

Fig. 17 is a sectoral view taken on the plane N—O of Fig. 16.

Fig. 18 is a diagrammatic side view of the structure of Fig. 16 after the hull bottom has been deflected upwardly to form the inclined run at the stern.

Fig. 19 is a section taken on the plane R—S of Fig. 18.

Fig. 20 is a diagrammatic end view of the hull shown in Fig. 18.

Fig. 21 is a diagrammatic plan view of the hull shown in Fig. 18 after the addition of the fantail which, as shown, may be constructed in accordance with the method disclosed in my co-pending application, Serial No. 264,090.

Fig. 22 is a diagrammatic section through a hull structure having bottom and sides and without a top deck.

Referring to Fig. 1, reference numeral 20 designates the initial tubular structure which may be formed of channel members encircling the structure and constructed in accordance with the method disclosed in my U. S. Patent 2,018,865, of October 29, 1935.

As disclosed in the patent, 2,018,865, the method comprises the initial pre-forming or bending of the structural members into ring-like shape, conforming to the transverse section of the hull, tacking a plurality of members together while they are held in alignment, to form unitary sections, welding the joints between the members in each of the units and combining a number of sections to form a hull structure.

The tubular structure 20, shown in Fig. 1 comprises the top 21, the side walls 30 and 31 and the bottom 22, and includes members which will

in the final hull structure, form the amidship's portion and also members for use in forming the bow and stern, or end portions, of the hull.

Figs. 3 and 4 represent the structure 20 of Fig. 1 after the top 21 and bottom 22 of same have been cut and the sectoral pieces have been removed to leave the "cut-outs" or openings 26 and 27 in the top 21 and openings 28 and 29 (see Fig. 4) in the bottom 22 of the tubular structure 20. The removing of the cut-outs 26 to 29 inclusive leaves the projecting walls 30 and 31 and also the projecting top deck portion 32 and the projecting bottom portion 33 attached to the amidship's portion 40 of the hull.

The cut-out 26 in the top 32 leaves the cut edges 34 and 36, and the cut-out 27 in the top 32 leaves the cut edges 35 and 37. Similarly, the cut-out 28 in the bottom 33 leaves the cut edges 42 and 44 and the cut-out 29 leaves the cut edges 43 and 45.

Figs. 5 and 6 represent the hull structure 20 after the projections 34 and 36 have been deflected inwardly so that the cut edges 34 and 36—35 and 37—42 and 44, and 43 and 45 are brought into contact and welded to complete the bow section of the hull.

It will be understood that if the channel construction shown in my U. S. Patents 2,018,865 and 2,104,053 is used it is preferable to run a flat bar header, of the same or greater depth than the channel flanges, between the contacting edges and weld the cut edges to each side of this bar. Such a header is shown at 54 in Fig. 12.

Figs. 7 and 8 represent in initial structure similar to that shown in Fig. 1, after cut-outs have been made in the top and bottom. In order to secure an overhang of the deck at the bow, the cut-outs 52 and 53 in the bottom of the initial structure are larger, as shown by the broken lines in Fig. 7, than the cut-outs 50 and 51 in the top of the structure.

Figs. 9 and 10 represent the structure after the cut edges have been deflected into contact as described above, and welded as shown to complete the bow of the hull.

As shown in Figs. 7 and 9 the initial hull structure does not include the forward portion 55 of the bow, which is added to the hull later as shown in Figs. 11 and 12. This construction can be used to advantage where the extreme forward portion of the bow 55 has straight sides.

It is pointed out that almost any desired shape of bow may be readily obtained by the use of cut-outs of proper contour and size in the top and bottom of the initial structure and proper shaping of the side walls. By bending the members forming the bow walls 30 and 31 to form concave sides in the forward portion of the initial structure and making the cut-outs larger in the bottom than in the top as shown in Figs. 7 and 8, a close approximation to a cutter bow may be obtained.

In deflecting the projections 30 and 31 into final position in the hull structure it is important that any buckling be avoided so that the cut edges will be brought into close contact for welding, and the lines of the hull maintained.

To obtain this result with a minimum of shoring, the method diagrammatically shown in Fig. 13 may be used. The initial hull structure 20 (as shown in Fig. 1) has rounded corners and the line of cutting, parallel to the walls 30 and 31, passes through the point of curve of such rounded corner. Thus, if a radius of three feet is used for the round, the line of cutting 160, as shown

in Fig. 13, would be parallel to and three feet from the face 161 of the wall.

In order that the deflection of the projections may be accomplished with ease, and a true line secured, it is necessary to remove transverse sectoral pieces 162 from the top and bottom curved portions of the side walls as shown in Fig. 13.

Should all these sectoral pieces be removed prior to deflection of the wall into position, it would be difficult to prevent buckling. To overcome this, the sectoral pieces are removed as shown at 163, leaving relatively small sections in place as shown at 164. As the bending or deflection proceeds these small sections 164 are each individually cut out in progressive order and the complete transverse cut, or slot, as at 162, is obtained only as each place or zone of bending is reached in the operation.

It will be understood that in the construction of ships of any size the projections 30 and 31 weigh many tons each and are deflected into position by means of hydraulic jacks, or tackle blocks. The deflecting force is applied near the end of the projection and the transverse cut farthest away is first completed and thus a long leverage is obtained, actually sufficient to curve the web of the channel members making up the side walls of the bow. As the deflection proceeds the cut edge 160 shown in Fig. 13 (this would correspond to cut edges 34, 35, 42 or 43 of Fig. 8) is brought into contact with the header 54 (see Fig. 12) as described, and immediately tack welded into position.

It will be noted that the curved corners of the deck and bottom are of great importance in providing reinforcement in the deflecting operation of the walls, and by progressive removal of the transverse pieces or slots from the walls, the bending is greatly facilitated and controlled.

Figs. 14 to 21 inclusive disclose the adaptation of the method specified to form the stern portion of the hull. Figs. 14 and 15 represent an initial hull structure 20 which would ordinarily be a part of the initial hull structure 20 shown in Fig. 1.

Figs. 16 and 17 represent the hull structure of Fig. 14 after a sectoral piece has been removed from the side walls 60 and 61, leaving the cut edges 64 and 65 in the side wall 60 and the cut edges 66 and 67 in the side wall 61. The bottom projection 62 is left attached to the amidship's section 40. 63 designates the top or deck.

Figs. 18 and 19 represent the hull structure after the bottom projection 62 has been deflected upwardly so that the cut edges 64 and 65 in wall 60 and the cut edges 66 and 67 in wall 61 have been brought into contact and welded.

It will be understood that if the curved corner construction, as shown, is used, the line of cutting will be at the point of curve in the side walls, as described above, and as the bending or deflection proceeds the transverse sectoral pieces will be progressively cut-out as shown in Fig. 13, for the purposes described.

As shown in Fig. 18 by dotted lines, and in Fig. 21, the stern of the hull may be closed in with a fantail construction as at 70 using the tapered members and the mode of assembly as described in my co-pending application, Serial No. 264,090.

As shown in Fig. 22, the hull structure may comprise a bottom member 90 and side wall members 91 and 92 attached to the bottom member by corner sections 93. In this case the triangular cuts would be made in the bottom 90 preliminary to bending the side walls inwardly to shape a conventional forward or bow end of the hull,

while cuts would be made in the side walls 91 and 92, at the other end of the structure, and the contiguous bottom lifted to shape a conventional stern portion of the hull. In both cases slots would be cut in the corner sections adjacent to the triangular cuts, to permit the members to be deflected into final position.

In the drawings I have shown the conventional type of ship having a pointed bow and a blunt stern, but it will be obvious that the methods specified may be used to construct other types, for example, barges with blunt ends or ships having other combinations of end shapes.

It will be obvious that the open stern of the hull, as shown in Fig. 20, may be closed in with a flat end or in any other desired manner.

In the construction of ships by the method described it will be understood that longitudinal and transverse bulkheads, intermediate decks, floors, hatches, deck houses, bridges, etc. will be used, all of which may be constructed as described in my co-pending application, Serial No. 264,090, and are not a part of the invention specified in this application.

I claim:

1. The method of constructing an end portion of the hull of a ship which comprises the initial forming of structural members to substantially the shape of the transverse section of the hull at its amidship's portion; joining said members to form a tubular parent structure having two pairs of oppositely disposed walls and open ends, and including members used in the amidship's and the end portions of the hull; cutting approximately triangular pieces from one pair of oppositely disposed walls of the parent structure, adjacent an end thereof, leaving projections in both pairs of said walls, which extend from the amidship's portion at said end; bending certain of said projections from the other pair of said walls, into respective adjacent relation with said projections in the first pair of said walls, to close the end and obtain the desired shape in the end portion of said hull and joining said projections to complete the said end of the hull.

2. The method of constructing an end portion of the hull of a ship which comprises the initial forming of structural members to substantially the shape of the transverse section of the hull at its amidship's portion; joining said members to form a tubular parent structure with open ends, and including members used in the amidship's and the end portions of the hull; cutting approximately triangular pieces from oppositely disposed walls of the parent structure, adjacent an end thereof, leaving projections which extend from the amidship's portion at said end; cutting slots in certain of said projections; bending said slotted projections into respective contact with the unslotted projections to close the end and obtain the desired shape in the end portion of said hull and joining said projections to complete the said end of the hull.

3. The method of constructing an end portion of the hull of a ship which comprises the initial forming of structural members to substantially the shape of the transverse section of the hull at its amidship's portion; joining said members to form a tubular parent structure with open ends, and including members used in the amidship's and the end portions of the hull; cutting approximately triangular pieces from oppositely disposed walls of the parent structure, adjacent an end thereof, leaving projections which extend from the amidship's portion at said end; pro-

gressively cutting slots in certain of said projections and progressively bending said slotted projections in the zone of the respective slots as they are cut, said slotted projections being bent to make contact with other of said projections to close the end and obtain the desired shape in the end portion of said hull and joining said projections to complete the said end of the hull.

4. The method of constructing an end portion of the hull of a ship which comprises the initial assembly and joining of structural members to form a tubular parent structure having curved corners connecting the four sides and with open ends, and in transverse section to conform substantially to the amidship's portion of the hull, said structure including members used in the amidship's and the end portions of the hull; cutting approximately triangular pieces from oppositely disposed walls of the parent structure, adjacent an end thereof, leaving projections which extend from the amidship's portion at said end; bending certain of said projections into respective contact with another of said projections to close the end and obtain the desired shape in the end portion of said hull and joining said projections to complete the said end of the hull.

5. The method of constructing an end portion of the hull of a ship which comprises the initial forming of structural members to substantially the shape of the transverse section of the hull at its amidship's portion; joining said members to form a tubular structure, with open ends, including members used in the amidship's and the end portions of said hull, and comprising a bottom, a deck and two oppositely disposed side walls connecting said bottom and said deck; cutting said bottom and said deck, from an open end of said structure, for the extent of said end portion, adjacent to each side wall; making additional cuts in said bottom and said deck to respectively intersect said first cuts and thereby removing two approximately triangular pieces from each, said bottom and said deck; bending the end portions of said side walls to bring the respective edges formed in said deck and bottom by said cuts, into abutting relation to substantially close the end of said structure, and joining said abutting edges to complete the end portion of the hull.

6. The method of constructing an end portion of the hull of a ship which comprises the initial forming of structural shapes, each into a member having four sides connected with curved corners; joining said members in transverse position to form a tubular structure, with open ends, having two pairs of oppositely disposed walls; cutting approximately triangular pieces from one pair of said walls extending from the ends thereof; bending the ends of the other pair of said walls to close an end of the structure and obtain the desired shape in said hull and joining the cut edges of said respective walls to complete the end portion of the hull.

7. The method of constructing an end portion of the hull of a ship which comprises the initial forming of structural shapes, each into a member having four sides connected with curved corners; joining said members in transverse position to form a tubular structure, with open ends, having two pairs of oppositely disposed walls; cutting approximately triangular pieces from one pair of said walls extending from the ends thereof; cutting slots in the curved corners of certain of the members forming the ends of the other

pair of said walls; bending the portions of the walls having the slotted corners to close an end of the structure and to obtain the desired shape in said hull and joining the cut edges of said respective cut walls to complete the hull.

8. The method of constructing an end portion of the hull of a ship which comprises the initial forming of structural shapes, each into a member having four sides connected with curved corners; joining said members in transverse position to form a tubular structure, with open ends, having two pairs of oppositely disposed walls; cutting approximately triangular pieces from one pair of said walls extending from the ends thereof; progressively cutting slots in the curved corners of certain of the members forming the ends of the other pair of said walls and progressively bending said last mentioned walls adjacent to each slot as it is cut to close an end and to obtain the desired shape in said hull of said structure and joining the cut edges of said respective cut walls to complete the end portion of the hull.

9. The method of constructing an end portion of the hull of a ship which comprises the initial forming of structural shapes, each into a member having four sides connected with curved corners; joining said members in transverse position to form a tubular structure, with open ends, and comprising a bottom, a deck and two side walls connecting said bottom and deck; cutting approximately triangular pieces from each of said side walls at one end of said structure; cutting slots in the curved corners of certain of the members adjacent to the bottom of said structure at said end; bending the said bottom at said end upwardly to substantially close the end and obtain the desired shape in said hull and joining the cut edges of said respective walls and bottom to complete the end portion of said hull.

10. The method of constructing the hull of a ship which comprises the initial forming of structural shapes, each into a member having four sides connected with curved corners; joining said members in transverse position to form a tubular structure, with open ends, having two pairs of oppositely disposed walls; cutting, for a certain distance from the end of said structure, one pair of said walls, along lines through the points of curve in said walls; making additional cuts in each of said last mentioned walls to respectively intersect said first cuts and thereby remove approximately triangular pieces from each of said cut walls in proximity to an end of said structure; cutting slots in the curved corners of certain of the members of the other pair of said walls at said end; bending the walls having the slotted corners at said end to obtain the desired shape in said hull and joining the cut edges of said respective cut walls to complete the hull.

11. The method of constructing an end portion of the hull of a ship which comprises the initial bending of standard shapes to form transverse members; joining a plurality of said members to form a substantially straight sided structure with open ends and having a bottom and side walls; cutting approximately triangular pieces from each of said side walls, at one end of said structure; bending the contiguous bottom upwardly to bring the cut edges of the respective walls into adjacent position and joining said cut edges to complete the end portion of said hull.

12. The method of constructing an end portion of the hull of a ship which comprises the initial forming of structural shapes, each into a member having a bottom and two side legs, said legs and

bottom being connected by curved corners; joining said members in transverse position to form a substantially straight sided structure, having a bottom and side walls; cutting approximately triangular pieces from each of said side walls at one end of said structure; cutting tapered slots in the curved corners of certain of the members of the bottom in proximity to the end of said structure; bending the contiguous bottom upwardly to bring the cut edges of the respective walls into adjacent position and to obtain the desired shape in said hull and joining the cut edges of the respective walls and bottom to complete the end portion of said hull.

13. The method of constructing an end portion of the hull of a ship which comprises the initial forming of structural shapes, each into a member having a bottom and two side legs, said legs and bottom being connected with curved corners; joining said members in transverse position to form a substantially straight sided structure having a bottom and side walls; cutting approximately triangular pieces from said bottom at one end of said structure; cutting tapered slots in the curved corners of certain of the members of the side walls in proximity to said end of the structure; bending the contiguous portions of the side walls inwardly to bring the edges of the cuts made in the bottom into respective adjacent position and to obtain the desired shape in the hull and joining said cut edges to complete the end portion of the hull.

14. The method of constructing the hull of a ship which comprises the initial forming of structural shapes, each into a member having a bottom and two side legs, said legs and bottom being connected by curved corners; joining said members in transverse position to form a substantially straight sided structure having a bottom and side walls; cutting approximately triangular pieces from each of said side walls at one end of said structure; cutting approximately triangular pieces from said bottom at the other end of said structure; cutting tapered slots in the curved corners of certain of said members at each end of said structure; bending the walls and bottom at the respective ends of said structure to obtain the desired shape in said hull and joining the abutting cut edges of said cut walls and bottom to complete the hull.

15. The method of constructing the hull of a ship which comprises the initial assembly and joining of structural pieces to form a tubular parent structure having open ends and comprising a bottom member, a deck member, and two side wall members connecting said bottom and said deck members; cutting approximately triangular pieces from each of said side walls at one end of said structure; cutting approximately triangular pieces from said bottom and said deck at the other end of said structure; bending the respective uncut members at each end of said structure to close the open ends of said structure and obtain the desired shape in said hull and joining the cut edges of said respective cut members to complete the hull.

16. The method of constructing the hull of a ship which comprises the initial assembly and joining of structural pieces to form a tubular parent structure having open bow and stern ends and comprising a bottom member, a deck member and two side wall members intermediate said bottom and deck members, said side walls being connected to said bottom and deck members by corner sections; cutting approximately triangular

pieces from said bottom and said deck at the bow end of said structure; cutting approximately triangular pieces from each of said side walls at the stern end of said structure; cutting slots in the corner section at each end of the structure adjacent to the respective cuts made in the bottom, deck and side walls; bending the side walls inwardly at the bow end and the bottom upwardly at the stern end of said structure to close the ends of said structure and obtain the desired shape in said hull and joining the cut edges of the respective cut members and corner sections to complete the hull.

17. The method of constructing an end portion of the hull of a ship which comprises the initial assembly and joining of structural members to form a tubular parent structure with an open end and comprising a bottom, a deck and two side walls connecting said bottom and deck; cutting approximately triangular pieces from each of said side walls adjacent to the open end of said structure; bending the bottom of said structure upwardly to substantially close the open end of said structure and obtain the desired shape in said hull and joining the cut edges of the respective walls to complete the end portion of said hull.

18. The method of constructing an end portion of the hull of a ship which comprises the initial bending of standard shapes to form transverse members; joining a plurality of said members to form a substantially straight sided structure with open ends and having a bottom and side walls; cutting approximately triangular pieces from the said bottom at one end of said structure; bending the contiguous side walls inwardly to bring the edges of the cuts made in the bottom into respective abutting position and joining said cut edges to complete the end portion of said hull.

19. The method of constructing an end portion of the hull of a ship which comprises the initial forming of structural channel shapes each having a web and two flanges, into members each having four sides connected with curved corners; joining said channel members, flange to flange, in transverse position to form a tubular structure, with open ends, having two pairs of oppositely disposed walls; cutting approximately triangular pieces from one pair of said walls, extending from an end thereof; cutting slots in the curved webs of certain of said channel members forming the adjacent ends of the other pair of said walls and bending the portions of said last mentioned walls adjacent to each slot to bring the cut edges into abutting position and to substantially close an end of said structure and joining the abutting edges of said respective cuts to complete the end portion of said hull.

20. The method of constructing an end portion of the hull of a ship which comprises the initial forming of structural channel shapes each having a web and two flanges into members each having four sides connected with curved corners; joining said channel members, flange to flange, in transverse position to form a tubular structure, with open ends, having two pairs of oppositely disposed walls; cutting approximately triangular pieces from one pair of said walls, extending from an end thereof; progressively cutting slots in the curved webs of certain of said channel members forming the adjacent ends of the other pair of said walls and progressively bending the portions of said last mentioned walls adjacent to each slot as it is cut, to bring the cut edges into abut-

ting position and to substantially close an end of said structure and joining the abutting edges of said respective cuts to complete the end portion of said hull.

21. The method of constructing an end portion of the hull of a ship which comprises the initial bending of standard structural channel shapes, each provided with a web and two flanges; joining said channel members, flange to flange, to form a parent structure with the channels extending transversely thereof, said parent structure comprising a bottom and two side walls attached to said bottom by curved corner sections; cutting approximately triangular pieces from said bottom, adjacent one end of said parent structure; cutting slots in the channel webs of the curved corner sections at each side of said structure, adjacent the said end of said structure; bending the contiguous portions of the side walls and corner sections inwardly to bring the edges of the cuts made in the bottom into respective abutting position and to obtain the desired shape in said hull, and joining the abutting edges in the bottom, and of the slots, to complete the end portion of the hull.

22. The method of constructing an end portion of the hull of a ship which comprises the initial bending of standard structural channel shapes, each provided with a web and two flanges; joining said channel members, flange to flange, to form a parent structure with the channels extending transversely thereof, said parent structure comprising a bottom and two side walls attached to said bottom by curved corner sections; cutting approximately triangular pieces from each of said side walls at one end of said parent structure; cutting slots in the channel webs of the curved corner sections at each side of said structure adjacent the said end of said structure; bending the contiguous end of the bottom upwardly to bring the edges of the respective cuts made in the side walls into abutting position and to obtain the desired shape in said hull and joining the abutting edges in the side walls and of the slots to complete the end portion of said hull.

23. In the art of shipbuilding the method of constructing a portion of a hull which comprises the initial bending of standard channel shapes to form two legs connected by a curved corner; assembling and joining said channel members to form a first wall section and a second wall section at substantially right angles to said first wall section, the individual channel members extending transversely through both walls sections, said wall sections being each originally substantially in one plane and connected to each other by a rounded corner section formed by the alignment of the curved corners of the transverse channel members; cutting an approximately triangular piece from the first wall section at an end thereof in proximity to the rounded corner section; progressively cutting tapered slots in the curved portions of the channel members, said slots adjoining the cut end of the first wall section; bending the second wall section, adjacent to each slot as it is cut, to bring the respective cut edges into abutting relation and form a curve in the deflected portion of said second wall section, and joining the abutting edges of said cuts to complete the construction of the said portion of the hull.

24. In the art of shipbuilding the method of building a portion of a hull which comprises the construction of a first wall section and a second

wall section at substantially right angles to said first wall section, each wall section being originally substantially straight and connected to each other by a curved corner section; cutting an approximately triangular piece from the first wall section at an end thereof in proximity to the curved corner section; cutting tapered slots in said corner section adjacent the cut end of the first wall section; bending the second wall section to bring the respective cuts into abutting relation and form a curve in the deflected portion of said second wall section and joining the abutting edges of said cuts to complete the building of the said portion of the hull.

25. In the art of shipbuilding the method of building a portion of a hull which comprises the construction of a first wall section and a second wall section at substantially right angles to said first wall section, each wall section being originally substantially straight and connected to each other by a curved corner section; cutting an approximately triangular piece from the first wall section at an end thereof, in proximity to the curved corner section; progressively cutting tapered slots in said corner section adjacent the cut end of the first wall section; bending the second wall section, adjacent to each slot as it is cut, to bring the respective cuts into abutting relation and form a curve in the deflected portion of said second wall section and joining the abutting edges of said cuts to complete the building of the said portion of the hull.

26. In the art of shipbuilding the method of building a portion of a hull which comprises the construction of a first wall section and a second wall section at substantially right angles to said first wall section, each wall section being originally substantially straight and connected to each other by a curved corner section; cutting an approximately triangular piece from the first wall section at an end thereof in proximity to the curved corner section; progressively cutting transverse tapered slots in said corner section, adjoining the cut end of the first wall section; bending the second wall section, adjacent to each slot as it is cut, to bring the respective cuts into abutting relation to form a curve in the deflected portion of said second wall section and joining the abutting edges of said cuts to complete the building of the said portion of the hull.

27. As a new article of manufacture, a hull for a ship, embodying construction in accordance with the method defined in claim 1.

28. As a new method of manufacture, a hull for a ship, embodying construction in accordance with the method defined in claim 3.

29. As a new article of manufacture, a hull for a ship, embodying construction in accordance with the method defined in claim 6.

30. As a new article of manufacture, a hull for a ship, embodying construction in accordance with the method defined in claim 7.

31. As a new article of manufacture, a hull for a ship, embodying construction in accordance with the method defined in claim 11.

32. As a new article of manufacture, a hull for a ship, embodying construction in accordance with the method defined in claim 14.

33. As a new article of manufacture, a hull for a ship, embodying construction in accordance with the method defined in claim 15.

34. As a new article of manufacture, a hull for a ship, embodying construction in accordance with the method defined in claim 16.

35. As a new article of manufacture, a hull

for a ship, embodying construction in accordance with the method defined in claim 18.

36. As a new article of manufacture, a hull for a ship, embodying construction in accordance with the method defined in claim 19.

37. As a new article of manufacture, a hull for a ship, embodying construction in accordance with the method defined in claim 21.

38. As a new article of manufacture, a hull

for a ship, embodying construction in accordance with the method defined in claim 22.

5 39. As a new article of manufacture, a hull for a ship, embodying construction in accordance with the method defined in claim 24.

40. As a new article of manufacture, a hull for a ship, embodying construction in accordance with the method defined in claim 26.

JOHN H. ODENBACH.
